(57) **CLAIM**

The ornamental design for a biopsy device for medical use, as shown and described.

DESCRIPTION

1. Biopsy device for medical use

1.1 : Perspective

1.2 : Front

1.3 : Back

1.4 : Left

1.5 : Right

1.6 : Top

1.7 : Bottom

The ornamental design for a biopsy device for medical use, as shown and described; the dashed broken lines in the drawings show portions of the biopsy device for medical use that form no part of the claimed design.
